UNITED STATES PATENT OFFICE.

FRANK E. JOHNSON, OF SALT LAKE CITY, UTAH, ASSIGNOR TO AMERICAN MANGANESE STEEL COMPANY, OF CHICAGO, ILLINOIS, A CORPORATION OF MAINE.

SCREEN.

1,312,545.

Specification of Letters Patent. Patented Aug. 12, 1919.

Application filed May 27, 1918. Serial No. 236,722.

To all whom it may concern:

Be it known that I, FRANK E. JOHNSON, a citizen of the United States, residing at Salt Lake City, in the county of Salt Lake 5 and State of Utah, have invented certain new and useful Improvements in Screens, of which the following is a specification.

My invention refers to screens and particularly to screens for use in screening ores 10 and other heavy materials.

In preparing ores and the like for use in concentrators and the like, it is desirable that all the waste material be separated to as great an extent as possible before the 15 ores and the like are delivered for further treatment. It is customary to permit the ores to ride down an inclined screen or slide so that the dirt, and the like will be sifted out and material delivered at the bottom 20 sufficiently screened for further treatment.

It is one of the objects of my invention to provide a screen having a roughened or wavy surface which will act as means for accelerating the screening action as the ores 25 pass down thereover.

Another object is to provide a screen which is so arranged as to serve as a means for causing a jarring or bumping of the ores and facilitating screening action.

30 A further object is to form a screen plate for use with ores and the like which is made of an integral plate having a series of transversely extending members curved in elevation and defining a plurality of screen openings in plan.

A further object is to improve screens and the like for successful commercial operation.

I accomplish these and other objects by 40 forming a screen plate preferably integrally, having a series of cross members defining spaces, the members in longitudinal elevation being wavy-like or curved, thus providing a plate having a series of wavy 45 portions on its surface.

Referring to the drawings:

Figure 1 is a top plan view of a screen made in the preferred embodiment of my invention.

50 Fig. 2 is a side elevation thereof.

Fig. 3 is a section on line 3—3 of Fig. 1, and

Fig. 4 is an enlarged sectional view on line 4—4 of Fig. 1.

55 The screen plate of my invention is made

as an integral plate comprising marginal members 5, 6, 7 and 8, longitudinally extending members 9 and transversely extending members 10, the various members being so cast as to define a series of regular shaped 60 openings 11 to serve as a screen or mesh. By varying the sizes of the openings 11, screens of various sizes of mesh may be made. For securing the screen plate in position, I prefer to make the marginal members 6 and 8 with flat bottoms, as shown in Fig. 2, and wavy upper portions 12, providing the same with properly arranged apertures 13 for the reception of suitable fastening means such as bolts, and the like. 70 The longitudinal and transverse members 9, 10, are wavy-like in elevation preferably in the form of a modified sine curve, although other wavy or curve-like shapes more or less acute, may be used if desired. The cross 75 section of the members 9, 10, in the form shown herein is substantially that of an inverted trapezoid, as shown at 14 in Fig. 3, but I do not wish to limit my invention to a bar having such a cross section as I propose to form screens having cross bars with cross sectional shapes such as circular, square, oblong, triangular, hexagonal, or of any other shape which may be required to meet different conditions of use. The purpose of providing a screen plate having a wavy upper surface is to serve as means for jarring or agitating the ores and the like 80 passing over the surface thereof. If desired, the screens may be set at an angle to the 90 direction of the travel of the ore, thus increasing the jarring or agitating action. If the ore were allowed to slide over a smooth screen the chances are that the dirt carried on the uppermost portion of the screen 95 would not be sifted out as the ore because of its great weight would move without any perceptible parting of the mass, whereas when directed over a screen of the form of my invention, the whole mass of ore will be 100 agitated to such an extent as to permit all dirt, and the like carried thereby to be sifted out and removed therefrom.

It will be noted that I have provided a 105 novel screen plate for screening heavy material such as ores, and the like, which of itself serves as a means for agitating the mass to pass therethrough, thus doing away with the necessity of mechanical agitation to remove waste.

Such modifications of such a device are susceptible and I consider as coming within my invention as defined by the appended claims.

5 I claim:—

1. An integrally formed screen, including boundary members and intermediate members, the boundary members having undulating upper surfaces.
- 10 2. An integrally formed screen, including boundary members and intermediate members, the boundary members having undulating upper surfaces and straight lower surfaces.
- 15 3. An integrally formed screen, comprising a plurality of members, including boundary members, each having curved upper surfaces for agitating the material being screened.
- 20 4. An integrally formed screen, comprising a plurality of members, including

boundary members, each having curved upper surfaces, adjacent members being curved in an opposite manner for agitating the material being screened.

5. An integrally formed screen, comprising a plurality of members, including boundary members, each having curved upper surfaces, and a plurality of transverse members similarly curved.

30 6. An integrally formed screen, comprising a plurality of members, including boundary members, the screening surfaces of which are undulating.

7. An integrally formed screen, comprising a plurality of undulating agitating members, including boundary members, the agitation being caused solely by said undulating members.

Signed at Salt Lake City, State of Utah, 40
this 7th day of May, A. D. 1918.

FRANK E. JOHNSON.
